GOGU CONSTANTINESCU, OF BLOOMSBURY, LONDON, ENGLAND.

APPARATUS FOR OBTAINING COMBUSTIBLE GAS.

1,111,995.

Specification of Letters Patent. Patented Sept. 29, 1914.

Application filed February 26, 1913. Serial No. 750,716.

To all whom it may concern:

Be it known that I, GOGU CONSTANTINESCU, a subject of the King of Roumania, and residing at 11 Hart street, Bloomsbury, London, W. C., England, have invented a certain new and useful Improved Apparatus for Obtaining Combustible Gas, of which the following is a specification.

This invention has for its object to provide an apparatus adapted to collect a part of the explosive gases under compression in the cylinders of an internal combustion engine, for the purpose of subsequently using these gases for illuminating or other purposes.

In application for British Letters Patent No. 26161 of 1912, I have described a method and apparatus for utilizing the pressure of the explosions in the cylinders of an internal combustion engine, for actuating a distributing device in such a way that the explosion in one cylinder will open a port for compressed gas leading from another cylinder of the motor. In such apparatus, two cylinders at least are required, and the cranks must be suitably placed relatively to each other.

The object of the present invention is to collect the combustible gases from an internal combustion engine having one or more cylinders, and the invention is applicable to motors having any number of cylinders.

According to the invention, I utilize the phenomenon that the combustible mixture used in internal combustion engines does not ignite throughout the entire length of a tube of small diameter, when a point of that tube is heated to a very high temperature. Thus, if a tube of sufficiently small diameter be filled with an explosive mixture of gas and air at any desired pressure, and if the mixture be ignited at one point in the tube by means of an electric spark or other means, combustion commences to the right and left of the point of ignition, but the flame stops at a certain point, owing to the fact that the heat generated by combustion is no longer sufficient to heat the successive gas layers to the temperature at which ignition takes place. Thus, if the tube is maintained at a low temperature, by any suitable means, the flame cannot be propagated along it.

The invention consists in drawing off combustible mixture from the cylinder of an internal combustion engine into a reservoir

through a long pipe of small diameter, provided at its outlet with a non-return valve, kept on its seat by a suitable pressure.

The invention further consists in apparatus for drawing off a portion of the combustible gases from the cylinders of internal combustion engines, comprising a long spiral tube of small diameter, fitted with a non-return valve at its outlet, and suitably cooled along its whole length.

The invention further consists in providing in connection with such a device for removing a portion of the combustible mixture a small reservoir provided with a cock, said reservoir discharging into another reservoir of any desired capacity.

In carrying the invention into effect, according to a simple example, as applied to an engine with only one cylinder I connect to the cylinder of the engine a tube of very small internal diameter, say two millimeters, made of a material which is a good heat conductor, so as to rapidly dissipate heat to the surrounding medium, as soon as a rise of temperature is produced in its interior. The end of the tube remote from the engine is fitted with a non-return valve, which will only allow a very small flow of gas to the outside when the pressure of the gas in the tube increases, and which will close completely when the outside pressure becomes greater than the pressure in the tube. The minimum length of the tube will depend on the flow allowed through the non-return valve. Suitable water cooling or other cooling means may be provided to cool the tube.

The operation of this apparatus is as follows:—At the instant when the engine begins its suction stroke, a fall of pressure is produced in the tube, and the gas contained therein is rarefied. During the compression stroke, the tube is filled with unburned combustible gases, and at the moment of explosion in the cylinder, the burned gases in the cylinder enter the tube, and compress in front of them the combustible gases which have previously entered, but ignition of these gases does not take place. The combustible gases are thus compressed to the outer end of the tube, and a portion of them will be delivered through the non-return valve; and if the valve is suitably proportioned, no part of the burned gases will pass through the non-return valve during the period of explosion in a cylinder.

On the exhaust taking place in the engine cylinder, the gases in the long tube expand, and the tube will be filled to a certain point with products of combustion along a part 5 of its length nearest to the engine, while unburned explosive gases will be contained at the outer end of the tube, these gases being under the pressure at which exhaust took place. During the second suction 10 stroke, the phenomena above described are repeated, and it will be seen that as a result of the continued rise and fall of pressure, a quantity of gas will be delivered through the non-return valve, which will be a mixture 15 of unburned gas and a small quantity of products of combustion, which remain in the tube after each exhaust. By suitably reducing the delivery aperture of the non-return valve, the quantity of products of 20 combustion in the gas can be reduced to a minimum. The reservoir connected to the tube thus becomes gradually filled with explosive mixture at a pressure increasing to the maximum pressure in the motor cylinder, during the firing stroke. The gases so 25 collected may be used directly for lighting or other purposes, or they may be enriched by passing them through benzol, petrol or the like, or if desired, a washing process 30 may be employed before utilizing the gases. It will thus be understood that if the discharge pipe of the aforesaid reservoir has a cock, such as will permit of drawing from the reservoir only a quantity that is strictly 35 limited by the length and diameter of the tube, the gases which pass out of the reservoir will be the purer, *i. e.*, more combustible, the smaller the delivery from the reservoir. The delivery from the reservoir should 40 therefore be determined by experiment until the quality of the gases thus obtained is satisfactory.

Referring to the accompanying drawings—Figure 1 is a view partly in section, showing my improved apparatus as applied 45 to a four-cylinder engine; Fig. 2 being a part section in a plane at right angles to Fig. 1.

In the form of the invention illustrated, 50 four spiral tubes, *a b c d*, are provided, each of which is in communication with a cylinder of the engine. The tubes are made of copper, and I have found that suitable dimensions, when applied to a four-cylinder 55 15 H. P. engine with a compression usual in petrol engines are to make the tube of 3 millimeters diameter and of about four yards total length. The tubes all lead into a small reservoir *e*, which is made capable 60 of withstanding the great pressure which would result from an ignition of the mixture in the reservoir at about 200 lbs. of greater compression pressure; and having regard to the small size of the chamber *e*, 65 sufficient strength is readily obtained, with-

out undue weight. At the outlet from each tube there is provided a non-return valve *f*, in the form of a disk having apertures around its circumference. The disk slides in a recess in the bottom of the chamber, 70 and is pressed lightly on to its seat by means of a spiral spring *g*. The outlet from the reservoir *e* is controlled by a needle valve *h*, and the gases from the chamber *e* pass through this valve into a reservoir 75 in which the pressure is reduced to say about 60 lbs. From this reservoir the gas is passed to another reservoir at the pressure at which the mixed gases are to be used. A suitable petrol tank is provided, 80 and the pipe leading from the regulator *h* leads the gases through the petrol in this tank, to wash out any oil which may be present.

In the above described apparatus, I have 85 found that a pressure of about 50 to 250 lbs. is suitable in the reservoir *e*, and this pressure can readily be kept sufficiently high at all loads of the engine by opening or closing the aperture leading from the reservoir by means of the valve *h*. When the engine is running at full load, the outflow from the reservoir may be increased. On stoppage of the engine, the petrol from the washing tank flows back through the valve 95 *h*, and fills the chamber *e*, and also leaks past the non-return valves *f*, completely filling up the tubes *a*, *b*, *c*, *d*, so that these tubes are washed out with petrol every time the engine stops, and the tubes are never 100 allowed to become dry, so that fouling of the tubes is delayed for a considerable time. It will be understood that the communication between the engine and the pipe must be closed during the stopping of the engine 105 to prevent the petrol flooding the cylinder of the engine. I find that sufficient cooling of the spiral tubes is obtained simply by the air current past them, and water cooling is not required.

The operation of this apparatus is similar 110 to that above described, and the dimensions given will be suitable for any engine in which the same pressures of compression before ignition and explosion pressure are 115 employed.

Having now described my invention, what I claim as new and desire to secure by Letters Patent is—

1. Apparatus for drawing off combustible 120 mixture from a cylinder of an internal combustion engine, comprising in combination a long pipe of small diameter in constantly open communication with the combustion chamber, a small reservoir communicating 125 with said pipe, and a non-return valve controlling the outlet from said pipe into said reservoir, as set forth.

2. Apparatus for drawing off combustible mixture from a cylinder of an internal com- 130

bustion engine, comprising in combination a long pipe of small diameter in constantly open communication with the combustion chamber, a small reservoir communicating with said pipe, a non-return valve controlling the outlet from said pipe into said reservoir, and means for controlling the outlet from said reservoir, as set forth.

3. Apparatus for drawing off combustible mixture from a cylinder of an internal combustion engine, comprising in combination a long spiral pipe of small diameter in con-

stantly open communication with the combustion chamber, a small reservoir communicating with said pipe, and a non-return valve controlling the outlet from said pipe into said reservoir, as set forth.

In testimony whereof I have signed my name to this specification in the presence of two subscribing witnesses.
